UNITED STATES PATENT OFFICE

2,463,261

MICROMETER HEAD

Charles F. Goodspeed, Norwood, R. I., assignor
of fifty per cent to Chester E. Wilbur, Oakland
Beach, R. I.

Application April 3, 1945, Serial No. 586,304

1 Claim. (Cl. 33—164)

1

This invention relates to a micrometer head. A primary object of the invention is the provision of a device adapted to be utilized in conjunction with a micrometer for measuring the degree of pressure applied to the micrometer screw, thus eliminating the element of "feel" or "touch" between two or more persons taking micrometer measurements on the same parts, such, for example, as a machine operator and an inspector.

An additional object of the invention is the provision of a device designed to eliminate the human element from micrometer measurements, thereby making measurements in ten thousandths of an inch practical and accurate to within the accuracy of the individual micrometer itself.

An additional object of the invention is the provision of an improved measurement device, characterized by extreme sensitivity, and so designed as to preclude minute differences in fine measurements.

Still another object is the provision of such a device which will be sturdy and durable in construction, exceptionally accurate and reliable in operation, and relatively simple and inexpensive to manufacture and assemble.

Further objects reside in the combinations of elements, arrangements of parts, and features of construction, all as will be more fully pointed out hereinafter and disclosed in the accompanying drawing where there is shown a preferred embodiment of this inventive concept.

In the drawings:

Figure 1 is a side elevational view, partially broken away, showing one form of head in accordance with this inventive concept.

Figure 2 is a longitudinal sectional view taken substantially through the center line of the device in Figure 1.

Figure 3 is an exploded plan view of certain constructional elements.

Figure 4 is a plan view of a constructional detail, and

Figure 5 is a sectional view taken substantially along the line 5—5 of Figure 2.

Similar reference characters refer to similar parts throughout the several views of the drawings.

Having reference now to the drawing, it will be seen that the device is comprised of a micrometer spindle 10, to which is secured a head cap 11, as by means of a screw 12. A micrometer thimble 13 surrounds the spindle 10, and has a head 14 in turn positioned thereabout. A counterhead 15 is also provided adjacent the juncture of the head and the thimble, and provided with the customary graduations 16.

Positioned in a suitable recess under the head cap 11 is a tension spring 17, one end of which is secured to an anchor pin 18, carried by the head.

2

The head 14 is provided with an internal flange 20, adjacent its upper extremity, in which flange is an elongated slot 21, into which extends a stop pin 22, secured to the upper portion of thimble 13.

From the foregoing the operation of the device should now be readily understandable. Head 14 is free to turn clockwise on thimble 13, as is the counterhead 15, to within the limits of the elongated slot 21, but is under counterclockwise tension of spring 17. In the operation, the head 14 is turned counterclockwise until the graduations on counterhead 15 are aligned with the graduations as desired on thimble 13, after which a reading may be taken in the usual manner. Thus, it will be seen that the spring 17 compensates for any variations in the individual's "touch" or "feel."

Means are provided for varying the spring tension of the spring 17, which means comprise loosening the screw 12 and turning the head cap 11 in either direction until the desired tension is produced. Screw 12 may then be re-tightened, and the micrometer reset to the new tension.

From the foregoing, it will now be seen that there is herein provided a device accomplishing all of the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

35 I claim:

In a device of the character described, a spindle, a thimble thereon, a head surrounding said thimble, an internal flange on said head having a slot therein, a pin on said thimble extending into said slot for limiting relative rotation between said flange and said thimble, and spring means rotationally biasing said thimble and said head, whereby said head is turned against the biasing resistance of the spring until the force of resistance set up by the said spindle which is anchored to said spring, is overcome.

CHARLES F. GOODSPEED.
